UNITED STATES PATENT OFFICE.

CHARLES S. SHALLENBERGER, OF ST. LOUIS, MISSOURI, ASSIGNOR TO SCULLIN-GALLAGHER IRON & STEEL COMPANY, OF ST. LOUIS, MISSOURI, A CORPORATION OF MISSOURI.

CAR-TRUCK.

No. 922,966.

Specification of Letters Patent. Patented May 25, 1908.

Application filed June 6, 1906. Serial No. 436,872.

To all whom it may concern:

Be it known that I, CHARLES S. SHALLENBERGER, a citizen of the United States, residing at St. Louis, Missouri, have invented a certain new and useful Improvement in Car-Trucks, of which the following is a full, clear, and exact description, such as will enable others skilled in the art to which it appertains to make and use the same, reference being had to the accompanying drawings, forming part of this specification, in which—

Figure 1 is a side elevational view of a portion of a car truck constructed in accordance with my invention; and Fig. 2 is a top plan view thereof.

This invention relates to new and useful improvements in car trucks.

A car truck of the type herein shown and described is provided with side frames having bolster-receiving openings and columns which form the sides of said openings, the bolster being slidingly mounted between said columns. In a truck of this type the shocks caused by stopping and starting the car cause the bolster to strike very severe hammer blows on the upper portion of the columns, and these hammer blows very often break or crack said columns.

In accordance with my invention the upper portion of each column is provided with a reinforcing rib which projects into the bolster-receiving opening and receives the shocks just referred to. These ribs also serve as guides for the bolster, and are adapted to coöperate with the standard type of bolster which is provided with pairs of guide lugs adjacent its ends.

Referring to the drawings, A indicates truck side frames, each of which is preferably in the form of a single casting provided with a rectangular bolster-receiving opening 1. The sides of the opening 1 are formed by columns 2 which are preferably channel-shaped and provided with a hollow reinforcing rib 3 which projects into the bolster-receiving opening.

B indicates a bolster provided with pairs

of guide lugs 4 which coöperate with the side faces of the ribs 3. Springs 5 are interposed between the bolster and spring seats 6. 50

To remove the bolster from the truck the first step is to remove springs 5 and allow the bolster to drop onto the spring seats 6. When the bolster is resting on the spring seats its guide lugs are out of alignment with 55 ribs 3, and it can be moved longitudinally through the openings in the side frames.

I do not deem it necessary to show or describe the wheels, journal boxes and various tie bars which are usually employed on a car 60 truck as these elements form no part of this invention.

I am aware that it is old to employ removable keys which project into the bolster-receiving opening and coöperate with the 65 bolster guides, but these keys weaken the columns at the point where they receive the greatest stresses.

Having thus described the invention, what is claimed as new and desired to be secured 70 by Letters Patent is:

1. In a car truck, side frames in the form of castings each having a rectangular bolster-receiving opening, spring seats, channel-shaped columns forming the sides of said 75 opening, each of said columns being provided with a hollow reinforcing rib which projects into said opening, said rib being formed integral with the column and located only on the upper portion thereof, a bolster having 80 pairs of guide lugs which coöperate with the side faces of said reinforcing ribs, and springs interposed between said bolster and spring seats; substantially as described.

2. A side frame for car trucks in the form 85 of a casting having a rectangular bolster-receiving opening, and columns forming the sides of said opening, the upper portion only of each column being provided with an integral rib which projects into said opening and 90 constitutes a bolster guide, said ribs being located directly opposite each other; substantially as described.

3. A side frame for car trucks in the form

of a casting having a rectangular bolster-receiving opening, columns forming the sides of said opening and having integral oppositely arranged projections extending into the upper portion only of said opening, in combination with a bolster having means for engaging said projections when the bolster is located in the upper part of the opening, said bolster being of such dimensions that it

may be removed when located in the lower part of the opening:

In testimony whereof I hereunto affix my signature in the presence of two witnesses, this first day of June 1908.

CHARLES S. SHALLENBERGER.
